UNITED STATES PATENT OFFICE.

WILLIAM H. SCHNEIDER, OF MILWAUKEE, WISCONSIN, ASSIGNOR TO ARTHUR C. KOOTZ, OF MILWAUKEE, WISCONSIN.

DIES.

Application filed February 11, 1925. Serial No. 8,442.

The invention relates to dies.

In the making of articles of various shapes from thin sheet metal, such as aluminum foil or from paper or other sheet material capable of being pressed or formed into the desired shape, it has been customary to shape the sheet material between specially made male and female dies with fixed impressions so that only one article of a certain shape could be produced with each set of dies. Such a procedure of forming the articles involved a great expense in die cost since a distinct set of dies had to be made for each particular form or article to be produced, and this situation has prevented the successful marketing of ornamental articles, such as Christmas-tree ornaments of standard form, up to the present time. One of the objects of this invention is to provide a die construction suitable for making ornaments or other articles in which one of the dies is so constructed and arranged as to conform to a great variety of shapes and sizes of forming dies, so that the cost of dies for forming the articles is materially reduced and ornaments of stamped form, such as Christmas-tree ornaments, made of thin sheet metal can be produced at a cost which will enable their successful marketing in competition with other types of ornaments for this purpose.

A further object of the invention is to provide a die construction in which one of the dies is used to press the material being formed against the forming die, said first-named die being composed of a plurality of independently movable elements that are yieldingly mounted so that they may be moved to automatically adjust themselves to conform to the shape of said forming die.

A further object of the invention is to provide a die construction whereby blanks of sheet material may be subjected to a corrugating process to form such blanks in articles of the desired shape.

The invention further consists in the several features hereinafter set forth and more particularly defined by claims at the conclusion hereof.

In the drawings: Fig. 1 is a plan view of an adjustable die member embodying the invention, parts being broken away and parts being shown in section;

Fig. 2 is a bottom view of one of the forming dies;

Fig. 3 is a vertical sectional view through the die embodying the invention, the forming die being shown in an upper position;

Fig. 4 is a view similar to Fig. 3, showing the forming die in its lower position;

Fig. 5 is a detail sectional view similar to Fig. 3, showing the forming die in an intermediate position;

Fig. 6 is a detail sectional view taken on the line 6—6 of Fig. 5;

Figs. 7 and 8 are detail sectional views of the sheet-holding parts of the dies, Fig. 7 showing the parts separated and Fig. 8 showing the parts in operative position;

Figs. 9, 10 and 11 are detail sectional views of forming dies of different shapes for use with the adjustable die;

Fig. 12 is an elevation view of an ornament fashioned by the die mechanism embodying the invention.

The adjustable die member includes a frame 14 having a plurality of radially disposed slots 15 formed therein and cooperating with a top frame member 16, secured to said frame 14, to form a plurality of radially disposed guideways which are preferably inclined upwardly, as shown in Fig. 3.

In each of the guideways formed as above described, a presser bar or member 17 is slidably mounted. Each of these bars is provided with a beveled edge 18 at its forming end which is also rounded, as at 19. Each bar is limited in its inward movement by a stop-pin 20 adjustably mounted on an arm 21 secured to the bar and engageable with a part of the frame, here shown as an annular surface 22. The bars are independently movable and are normally pressed inward to their "stop" position by means of a strong rubber band 23 which engages the end 24 of each bar.

The forming die 25 may be of any shape desired, either symmetrical or unsymmetrical, and where a corrugated article is to be formed is provided with a fluted or corrugated surface 26, and is so aligned relative to the adjustable die that the beveled edges 18 of the presser bars line up with the bottoms of the flutes or radially disposed corrugations 27, as shown in Fig. 6. This forming die may be moved relative to the adjustable die, in any suitable manner, and is generally moved up and down by connection of an operating rod 28 with a suitable press mechanism. A forming die of one shape is shown

in Fig. 3 and forming dies of other shapes that may be used in connection with the adjustable die are shown in Figs. 9, 10 and 11.

With the above construction a piece of sheet material, as metal foil, paper or other material, is placed between the dies and then as the forming die 25 descends and moves past the presser bars 17 the material is formed by said bars into the shape of the forming die, since the bars are forced outwardly by said die 25 as the material with said die moves over said bars. As the presser bars readily conform to various shapes which the forming die may have, a great variety of articles may be made with a single adjustable die.

In some instances I find that it is desirable to exert pressure upon the material being shaped without permanently clamping it during the forming operation, and for this purpose I provide a presser or clamping member 29 movable with and relative to the forming die and cooperating with a fixed member 30 on the top of the adjustable die. For corrugated articles these members 29 and 30 are provided with radially disposed corrugations 31 and 32 adapted to register as shown in Fig. 8, the corrugation 32 being alined with those formed on the forming die. The member 29 is connected with the die 25 by means of a cylindrical part 33 which forms a guide for the forming die 25 connected by screws 34 with cap member 35 slidably mounted on the rod 28 and alined with the die 25 by means of a pair of spaced guide rods 36 secured to the base of the forming die and projecting through openings 37 in said cap 35. The member 29 may, when moved to an operative position, be held against the material 38 by its own weight or by pressure from a spring 39.

The action of the dies is shown in Figs. 3 to 5, inclusive, and the manner in which the material is temporarily held while being pressed into shape is shown in Fig. 8. This clamping pressure exerted upon the material by the members 29 and 30 is preferably only such as to offer some resistance to the movement of the material but not such as to prevent the material from slipping or sliding between said members as the forming die 25 carries the material past the presser bars. Thus, it will be understood that the die is not of the type in which material being acted upon is drawn or attenuated, but the shaping is produced by a bending and ironing action. It is noted that the members 29 and 30 prevent the material from crinkling, especially in the case of sheet metal, and assist in the formation of the material prior to its passage to the forming die.

The forming die 25 preferably works through a guide opening 40 in the frame 14, and after the material passes the presser bars it moves into this opening and then

either falls from the die or may be readily removed therefrom.

In making Christmas-tree ornaments consisting of two complementary sections that are joined together to form the finished ornament, the forming die is preferably provided with an inclined annular edge 41 by which a flange may be made on each section of the ornament for use in the subsequent operation of joining the two sections together.

In Fig. 12 I have shown a bell-shaped ornament 42 formed by pressing a circular blank of metal foil between the adjustable die and a forming die, such as shown in Fig. 10.

In instances where the shapes are irregular, each of the presser members may be urged inwardly by its own spring, as shown in Fig. 4, where a spring 43 is connected to the arm 21 and to a pin 44 on the top frame 16.

I desire it to be understood that this invention is not to be limited to any particular form or arrangement of parts except in so far as such limitations are specified in the claims or necessitated by the prior art.

What I claim as my invention is:

1. A die, comprising a forming and blank-feeding member and a die co-operating therewith to form the material about said forming member as said material is moved past said die including a plurality of presser members movable relative to the forming member, and means for yieldingly urging said presser members into operative action with the forming member, said presser members permitting the use of forming dies of various shapes.

2. Apparatus for forming sheet material into articles of various shapes, comprising a forming die having a corrugated surface, a cooperative die member including a plurality of presser members movable relative to the forming die and alined with the corrugations in said die to shape the material over said die as it moves past said presser members, and means for yieldingly holding the presser members to their work, said presser members being adapted to accommodate forming dies of various shapes and sizes.

3. In a die construction, the combination with a forming die having a corrugated surface, of a plurality of presser members adapted to cooperate with the corrugations in said surface and movable relative thereto to shape and form the material over said surface as it is carried past said presser members by the forming die, of clamping members adjacent the forming die and having corrugations alined with the corrugations of the forming die to produce pressure upon said material and assist in its formation prior to the passage of said material between said clamping members to the forming die.

4. In a die construction, the combination of a forming member, of a die member co-operating therewith, a plurality of radially disposed movable presser members, adjustable means limiting the inward movement of said members, and yieldable means resisting the outward movement of said members as said members are moved by said forming die when the material on said forming die is carried past said members.

5. In a die construction, the combination with a forming die, of a cooperative die member, comprising a frame provided with radially disposed inclined guideways, a presser member slidably mounted in each of said guideways, adjustable means between each presser member and the frame for limiting the inward movement of each presser member, and means for moving and yieldably holding said presser members in their inner or "stop" position, said means permitting the outward movement of said presser members under the action of said forming die.

6. In a die construction, the combination with a forming die, of a cooperative die member, comprising a frame provided with radially disposed inclined guideways, a presser member slidably mounted in each of said guideways, adjustable means between each presser member and frame for limiting the inward movement of each presser member, and means engageable with all of said presser members for yieldingly maintaining said presser members in "stop" position and permitting their movement outwardly under the action of the forming die.

7. In a die construction, the combination with a forming die, of a cooperative die member, comprising a frame provided with radially disposed inclined guideways, a

presser member slidably mounted in each of said guideways, adjustable means between each presser member and frame for limiting the inward movement of each presser member, and a yieldable band engaging said presser members to move them to a "stop" position.

8. In a die construction, the combination of a forming member having a forming face and an annular flange at the base of said face, of means including a plurality of movable yieldingly tractible presser members to shape the material to conform to the shape of the face of said forming member and said flange as it moves past said members.

9. A die, comprising a forming and blank-feeding member and a die cooperating therewith to form the material about said forming member including a plurality of presser members movable relative to each other and to the forming member by the forming member, and means for urging said presser members into operative action with the forming member, said presser members permitting the use of forming dies of various shapes.

10. Apparatus for forming sheet material into articles of various shapes, comprising a forming and blank-feeding die having a corrugated surface, a cooperative member including a plurality of presser members movable relative to each other and to the forming die and alined with the corrugations in said die to shape the material over said die as it moves past said members, and means for yieldingly holding the presser members to their work, said presser members being adapted to accommodate forming dies of various shapes and sizes.

In testimony whereof, I affix my signature.

WILLIAM H. SCHNEIDER.
